UNITED STATES PATENT OFFICE.

JOHN L. JANISCH, OF CHICAGO, ILLINOIS.

CONCRETE-FORM.

1,217,003.

Specification of Letters Patent. Patented Feb. 20, 1917.

Application filed September 24, 1915. Serial No. 52,444.

To all whom it may concern:

Be it known that I, JOHN L. JANISCH, a citizen of the United States, and a resident of the city of Chicago, county of Cook, and 5 State of Illinois, have invented certain new and useful Improvements in Concrete-Forms, of which the following is a specification.

My invention relates to improvements in 10 concrete molds especially adapted for use in forming burial vaults, caskets and the like, the object of the invention being to provide an improved construction of this character which is simple and efficient in 15 use.

The invention consists in the combinations and arrangements of parts hereinafter described and claimed.

The invention will be best understood by 20 reference to the accompanying drawings forming a part of this specification, and in which,

Figure 1 is a side view of a mold arranged to form the body of a burial vault, embodying my invention,

Fig. 2, a longitudinal section of the same taken on line 2—2 of Fig. 1,

Fig. 3, a top plan view of the same,

Fig. 4, a transverse section taken on line

30 4—4 of Fig. 3.

Fig. 5, an enlarged perspective view of 35 a corner joint employed in the core of the mold, and

Fig. 6, a similar view showing parts de- 40 tached.

The preferred form of construction of 45 mold for forming the body of the vault comprises a base plate 15 and removable side members 16 and end members 17 removably arranged on said base member to constitute the outer wall of the form. Cleats or stops 18 and 19 are arranged on the base member 15 in positions to engage the lower edges of the side and end members 16 and 17 to 50 limit outward movement thereof. The end members 17 are curved at their extreme ends to constitute corners of the outer mold form and are connected with the side members 16 by means of stepped joints 20, as indicated in Fig. 3. Slidable strips 21 are slidably secured to the outer sides of side members 16 by means of slot and bolt connections 22 whereby said slides may be fitted over the stepped joints 20 to further position the end members 17 in place. A substantially U-shaped clamping member 23 is arranged around the sides and across one

end of the form thus produced, the ends 24 of the sides thereof being threaded and fitted through perforations in a yoke 25 and 60 equipped with binding nuts 26 whereby the walls of the form may be securely bound or clamped together.

An inner collapsible core is arranged on the base member 15 to coöperate with the 65 outer form member just described, said core member comprising side members or walls 27 and end members 28, said side and end members being connected together at the corners by inwardly movable corner members 29 having stepped joints 30 with the corresponding side and end members, as best illustrated in Figs. 3, 5 and 6. Slides 31 are slidably secured to the inner walls of the side and end members 27 and 28 by 70 means of bolt and slot connections 32 and by means of which the corner members 29 may be secured in place or released for inward movement in collapsing the core.

The side members 27 and the end members 28 are provided with centrally positioned downwardly projecting securing pins 33 and 34 respectively, arranged to fit within corresponding openings in base 15 to position the lower ends of said core members. 80 A core top member 35 is arranged to fit within the side and end members 27 and 28 resting upon supports 36 in the form of angle members secured to the inner walls of said side and end members, the horizontal legs of said angle members being perforated to receive downwardly projecting pins 37 on said top member 35. The top member 35 is provided on its under side with a centrally positioned handle ring to 95 assist in manipulating the same. A V-shaped rib 39 is formed on the base member 15 between the outer form and the inner core to form a V-shaped groove in the corresponding portion of the vault. 40 100 formed in the mold.

In use, the parts are assembled as best indicated in Figs. 1, 2, 3 and 4, and the space between the core member and the outer form member and above the core member filled 105 with a suitable concrete mixture in the usual manner. After this mixture has set or become hardened the nuts 26 are loosened and the clamping member 23 removed. Thereupon nuts 22 are loosened and the slide 110 members 21 moved back to facilitate removal of the side and end members 16 and 17. Then the form is turned upside down, and the base member 15 removed. This

gives access to the interior of the core member and the corner members 29 are readily removed therefrom by loosening the bolts of the connection 32 which permits of the ready removal of the side and end members. Then the core top member 35 is removed by means of handle member 38, thus finishing the operation.

10 The form of construction set forth will be found to be a simple and efficient one for the purpose.

15 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations 20 and modifications as come within the scope of the appended claims.

Having described my invention what I claim as new and desire to secure by Letters Patent is:

25 1. A concrete mold comprising an outer form consisting of removable side members joined together at the corners; slides on the outer sides of said members arranged to cover said joints; a collapsible core for said outer form consisting of removable side members joined together at the corners by inwardly movable corner members; and means on the inside of said core arranged to lock said corner members temporarily 30 against such inward movement, substantially as described.

40 2. A concrete mold comprising an outer form consisting of removable side members joined together at the corners by a stepped joint; slides on the outer sides of said side members arranged to cover said joints; a clamping member arranged to bind said side members together; a collapsible core for said outer form consisting of removable 45 side members joined together at the corners by inwardly movable corner members; and means on the inside of said core arranged to lock said corner members temporarily 50 against such inward movement, substantially as described.

55 3. A concrete mold comprising an outer form consisting of removable side members joined together at the corners by a stepped joint; slides on the outer sides of said side members arranged to cover said joints; a clamping member arranged to bind said side members together; a collapsible core for said outer form consisting of removable 60 side members joined together at the corners by inwardly movable corner members; and slides on the inner sides of said side members of said core arranged to lock said cor-

ner members temporarily against such inward movement, substantially as described.

4. A concrete mold comprising an outer 65 form consisting of removable side members joined together at the corners by a stepped joint; slides on the outer sides of said side members arranged to cover said joints; a clamping member arranged to bind said side members together; a collapsible core for said outer form consisting of removable 70 side members joined together at the corners by inwardly movable stepped corner members; and means on the inside of 75 said core arranged to lock said corner members temporarily against such inward movement, substantially as described.

5. A concrete mold comprising an outer 80 form consisting of removable side members joined together at the corners by a stepped joint; slides on the outer sides of said side members arranged to cover said joints; a clamping member arranged to bind said side members together; a collapsible core for 85 said outer form consisting of removable side members joined together at the corners by inwardly movable stepped corner members; and slides on the inner sides of said side members of said core arranged to lock said 90 corner members temporarily against such inward movement, substantially as described.

6. A concrete mold comprising a base; an outer form consisting of removable side members joined together at the corners by a stepped joint; slides on the outer sides of said side members arranged to cover said joints; a clamping member embracing the sides of said form and binding the same together; a collapsible core for said form 100 consisting of removable side members detachably connected with said base within said outer form and distanced therefrom, said side members being joined together at the corners by inwardly movable stepped 105 corner members; slides on the inner sides of said core members arranged to lock said corner members temporarily against inward movement; a top member for said core arranged to fit within said side members; supports for said top member on the inner sides 110 of the core side members; pins on said top member, there being corresponding openings in said supports to receive said pins; and a handle member arranged centrally on 115 the under side of said top member, substantially as described.

In testimony whereof I have signed my name to this specification in the presence of two subscribing witnesses.

JOHN L. JANISCH.
